UNITED STATES PATENT OFFICE.

WALTER EVERETT MAINES, OF BERLIN, NEW HAMPSHIRE.

HOT-WATER HEATING SYSTEM.

Application filed September 11, 1922. Serial No. 537,887.

To all whom it may concern:

Be it known that I, WALTER EVERETT MAINES, a citizen of the United States, residing at Berlin, in the county of Coos and 5 State of New Hampshire, have invented a new and useful Hot-Water Heating System, of which the following is a specification.

This invention relates to hot water heating systems for use in connection with kerosene stoves, and more particularly to kerosene cook stoves.

The object of the invention is to provide a hot water heating system for use with kerosene stoves so constructed that the water will be heated by the same burner which cooks the food without in any way interfering with the cooking operation.

Another object is to provide a funnel capper pipe for use in connection with a hot water heating heater of this character which is constructed so as to permit the funnel to be easily removed to afford access to the burner for cleaning and other purposes without interfering with the heating coils and 25 without requiring any fasteners.

With the foregoing and other objects in view which will appear as the description proceeds, the invention resides in the combination and arrangement of parts and in 30 the details of construction hereinafter described and claimed, it being understood that changes in the precise embodiment of the invention herein disclosed may be made within the scope of what is claimed without departing from the spirit of the invention.

In the accompanying drawings:—

Figure 1 represents a side elevation of a kerosene cook stove in connection with this improved water heating system.

Fig. 2 is a vertical section through one of the capper pipes used on the burners of an oil stove, with the water heating coil shown in elevation therein.

Fig. 3 is a top plan view thereof, and

Fig. 4 is a rear elevation thereof.

In the embodiment illustrated, a kerosene cook stove S is shown equipped with the usual burners B, any desired number of which may be employed, three being here 50 shown.

Each of the burners B is surmounted by a funnel capper pipe 1 such as is ordinarily used with burners of this character, the only difference being that the capper used in connection with this system is split longitudi-

nally from end to end preferably at an oblique angle as shown at 2 and the walls of this split portion have registering recesses to provide passages 3 and 4 for the inlet and outlet portions of the heating coil 5. 60 This coil 5 which is mounted in the pipe 1 is preferably helical in form with the larger end disposed at the bottom and connected at its upper and lower ends by unions 7^a and 8 with supply and return pipes 7 and 9 65 respectively which lead to a boiler 6. The supply pipe 7 extends into the bottom of the boiler while the return pipe 9 which takes the hot water to the boiler opens through the top thereof as is ordinary in boilers of 70 this character. A hot water pipe 10 leads from the top of the boiler 6 for conducting the water to the bath or sink or any other point where it is to be used.

A drain cock 11 is shown connected with 75 the supply pipe 7 at the lower portion thereof so as to drain the boiler when desired. The capper pipes 1 are each provided at their front faces with a door 12 to afford access to the burner for lighting and the like. These capper pipes 1 are also provided at their upper ends with the usual annular covers 1^a which assist in retaining the pipes against separating which might otherwise occur owing to the longitudinal splitting thereof to facilitate its removal from the burner which is desirable for cleaning and other purposes. To remove this pipe 1 without in any way affecting the heating coil 5, the cover 1^a is detached and the pipe 1 80 spread or expanded sufficiently to disengage the seats 3 and 4 thereof from the upper and lower ends of the coil 5, thereby permitting the cap to be readily removed. To replace it, the operation above described is reversed.

From the above description it will be obvious that a stove equipped with this heating system will, when the burners are lit, immediately heat the water flowing through the coils 5 in a manner well known in systems of this character and yet may be used for cooking food in the ordinary way so that when a burner is lit for cooking the water in the coil surrounding it is immediately heated and flows into boiler 6 ready for use 105 when desired.

A system of this character constructed as herein shown and described is simple and cheap to manufacture and may be applied to any kerosene stove by simply providing 110

additional copper pipes 1 as substitutes for those usually employed with stoves of this character.

I claim:—

- 5 The combination with a cook stove having a burner with a copper pipe surrounding it, a helically coiled water pipe arranged in said copper pipe directly over said burner and having a supply and return pipe connected therewith, said copper pipe being
- 10 split longitudinally and obliquely and having registering recesses in the walls of said

split portion to form seats for the inlet and outlet portions of the coils, and a flanged annular cover fitting over the upper end of 15 said copper pipe to retain it against opening and to permit the free passage of heat.

In testimony that I claim the foregoing as my own, I have hereto affixed my signature in the presence of two witnesses.

WALTER EVERETT MAINES. U. S. 1
